SHIPPING CASE

Byron F. Kelly, Worcester, Mass.

Application December 5, 1934, Serial No. 756,101

10 Claims. (Cl. 217—20)

This invention relates to an improvement in shipping cases and more particularly to shipping cases having a plurality of compartments adapted to receive bottles or other frangible articles and to hold them in predetermined position to prevent breakage or rattling.

The primary object of this invention is to provide a shipping case of this type in which certain or all of the walls forming the compartments are provided with buffers which bear against the articles, such buffers being in the form of blocks of rubber or similar material carried by the walls and projecting outwardly therefrom.

More specifically this invention is adapted for use in shipping boxes or carriers for milk bottles to prevent the bottles from clanking or rattling and hold them upright in the carrier while the carrier is in motion.

These and other objects will appear from a consideration of the following description of this invention and of the drawing which forms a part thereof and in which

Fig. 1 is a plan view of a shipping box embodying this invention;

Fig. 2 is a sectional side elevation of a portion of the box shown on an enlarged scale;

Fig. 3 is a plan view broken in part, of a divider for the box;

Fig. 4 is a perspective view of one of the blocks forming buffers and adapted to be mounted in the dividers; and

Fig. 5 is a perspective view of a portion of a divider and block taken in section along the line 5—5 in Fig. 2.

This invention is illustrated as applied to a shipping box or carrier for milk bottles and will be so described. It will be understood however that the invention is not so limited and is applicable to shipping boxes of other kinds and adapted for other uses.

The carrier 20 comprises end and side walls 21 and 22 respectively connected by a plurality of dividers 23 and supports 24. The dividers 23 are, as shown in Fig. 2 arranged at two levels and form with the walls of the carrier a plurality of compartments 25 substantially of the same dimensions. Each compartment is adapted to receive a milk bottle which rests upon the supports 24, here shown as rods which preferably are covered with tubing of rubber or similar material.

The dividers 23 are metal strips which originally are of the form shown in Fig. 3 having a plurality of bowed portions 26 in each of which are a pair of parallel slots 27 arranged at opposite

sides of and equidistant from the longitudinal center line of the strip. The portions 26 are separated by more restricted portions 28 each of which has an opening 29 therein.

Carried by the dividers 23 are a plurality of buffer blocks 30 of rubber or similar material. Each block 30 has on two opposite faces flanges 31 (see Fig. 4). The portions 26 are bent into a conformation U shaped in cross section in which is inserted a block 30 as shown in Fig. 5, the sides of the block 30 projecting through the slots 27 and the flanges 31 being enclosed between the legs of the portion 26.

The dividers 23 are then assembled to form with the carrier walls the sides of the compartments 25. The ends of the dividers normally extend to the walls of the carrier and are secured in position in any suitable manner. Thus in the present embodiment the ends of the dividers are inserted between the boards forming the walls 20 and secured thereto by double ended nails 35 which pass through the end openings 29. The portions 28 overlap at the corners of the compartments with the openings 29 in register to permit securement thereto of the ends of the posts 36 which thus connect the two levels at the intersections of the dividers.

The sides of the compartments defined by the dividers 23 thus carry the buffer blocks 30 substantially midway between the corners. The remaining sides of the compartments are formed by the walls of the carrier. The bottles in certain of the compartments bear against the buffer blocks 30 and in others against the buffer blocks and the walls of the carrier. They are thus held from any contact with the metal of the dividers. Moreover the blocks being of rubber or similar material yieldably hold the bottles in place. The bottles rest upon the rubber covering of the divider rods 24 and thus any danger of rattling or clanking when the carrier is in motion is prevented.

Heretofore attempts have been made to make carriers of this type by using rods as dividers and covering the middle portions at each compartment with rubber tubing. It, however, has been found difficult to secure the tubing in place. Moreover these carriers are always washed with hot water and the heat thereof causes the tubing to expand thus allowing moisture to enter so that the carriers are not entirely sanitary. Carriers embodying the present invention are not subject to these difficulties. The buffer blocks are within and not around the dividers and hence the expansion due to the heat of the washing water causes

the blocks to bear more closely against the walls of the slots.

The buffer blocks as they become worn or torn can be replaced without difficulty and without the necessity of removing any divider from the carrier. The legs at the sides of the block to be replaced are spread apart sufficiently to allow the insertion of a new block and are then restored to the position shown in Fig. 5. The flanges 31 5 as shown in that figure fill the portion of the U above the block and substantially close the portion below the block.

While one embodiment of this invention has been shown and described it will be understood 15 that I am not limited thereto and that other embodiments thereof may be made without departing from the spirit and scope of the invention as set forth in the following claims.

I claim:

- 20 1. In a shipping box having a plurality of article receiving compartments the sides of which are formed by dividers or by the walls of the box, means for holding the articles in the compartment comprising buffer blocks carried by the 25 dividers one in the middle of each side of the compartment so formed, the portions of said dividers at which the blocks are carried being U shaped in cross section.
2. In a shipping box having a plurality of 30 article receiving compartments the sides of which are formed by dividers or by the walls of the box, means for holding the articles in the compartment comprising buffer blocks carried by the dividers one in the middle of each side of the compartment so formed, the portions of said dividers at which the blocks are carried being U shaped in cross section with slots in the legs thereof, portions of said blocks projecting through the slots beyond the outer surfaces of the legs whereby the 35 blocks only contact with the articles.
3. In a shipping box having a plurality of article receiving compartments the sides of which are formed by dividers or by the walls of the box, means for holding the articles in the compartment comprising buffer blocks carried by the 40 dividers one in the middle of each side of the compartment so formed, each block having flanges on opposite sides thereof, the portions of said dividers at which the blocks are carried being U shaped in cross section with slots in the legs thereof, portions of said blocks projecting through the 45 slots beyond the outer surfaces of the legs and the flanges being enclosed between said legs.
4. A bottle carrier having a plurality of compartments each adapted to receive a bottle, including dividers, which with the walls of the carrier form the sides of the compartments and buffer blocks carried by the dividers and project-

ing into the compartments from the middles of the sides formed by the dividers, the portions of said dividers at which the blocks are carried being U shaped in cross section with slots in the legs thereof and portions of said blocks projecting through the slots beyond the outer surfaces of the legs whereby the blocks alone contact with the bottles at the divider sides of the compartments. 5

5. In a bottle carrier having a plurality of compartments each adapted to receive a bottle a divider having separated portions U shaped in cross-section and buffer blocks carried by such portions. 10

6. In a bottle carrier having a plurality of compartments each adapted to receive a bottle a divider having separated portions U shaped in cross-section and buffer blocks at such portions inserted in the U and projecting outwardly therefrom. 15

7. In a bottle carrier having a plurality of compartments each adapted to receive a bottle a divider having separated portions U shaped in cross-section and having a slot in each leg thereof and buffer blocks at such portions inserted in the 20 U portions of said blocks projecting through said slots beyond the outer surface of the legs. 25

8. A shipping box having a plurality of compartments the sides of which are formed by the walls of the box or by dividers, said dividers being 30 of formed metal, flat at their intersections at the corners of the compartment and U shaped in cross section midway between such corners to provide downwardly open pockets, and buffer blocks carried in said pockets and projecting 35 laterally therefrom into contact with the articles carried in the compartments.

9. A shipping box having a plurality of compartments the sides of which are formed by the walls of the box or by dividers, said dividers being 40 of formed metal, flat at their intersections at the corners of the compartment and U-shaped in cross section midway between such corners to provide downwardly open pockets, the walls whereof having slots therein and buffer blocks 45 carried in said pockets and projecting through said slots into said compartments.

10. A shipping box having a plurality of compartments the sides of which are formed by the walls of the box or by dividers, said dividers having, in the middle of each side, open pockets, the mouths of which are downward, the walls of said pockets having slots therein and buffer blocks carried in said pockets and projecting from said 50 slots into contact with the articles carried in the 55 compartments.
